UNITED STATES PATENT OFFICE.

DUDLEY J. MORTON, OF PHILADELPHIA, PENNSYLVANIA.

DEVICE FOR THE PREVENTION AND TREATMENT OF DEFORMED FEET.

Original application filed March 2, 1915, Serial No. 11,453. Divided and this application filed April 5, 1920. Serial No. 371,531.

To all whom it may concern:

Be it known that I, DUDLEY J. MORTON, a citizen of the United States, residing at Philadelphia, county of Philadelphia, and 5 State of Pennsylvania, have invented new and useful Devices for the Prevention and Treatment of Deformed Feet, of which the following is a specification.

This application is a division of my co-pending application on which Letters Patent 10 No. 1,335,981 were granted April 6, 1920, and relates to improvements in methods and means for the prevention and treatment of deformed feet.

15 The bone structure of the foot may be divided into anterior and posterior portions. The latter consists of the astragalus and os calcis, and it is upon this portion that the leg bones are borne, the os calcis being 20 lowermost. The anterior portion comprises the scaphoid (which articulates with the astragalus) the cuboid which articulates with the os calcis and the cuneiform, metatarsal and phalangeal bones. Most of the 25 joints of the foot present flattened surfaces permitting very little motion. This, however, is not so at the junction of the anterior and posterior portions of the foot. At this point the bone surfaces are curved, especially 30 the head of the astragalus where it articulates with the scaphoid and the os calcis where it articulates with the cuboid. By reason of the contour of the bones mentioned, 35 relatively free movement of the joints formed thereby is permitted.

The foot as a base of support presents 40 two divergent bony margins meeting at the heel, the centre of weight-bearing lying therebetween. Owing to some fault leading to flat foot, the center of weight bearing moves toward the inner line and should this center pass the inner line the balance of the foot is lost. Under such a condition, 45 the weight, instead of being borne upon a stable bony structure, is sustained by a soft structure of muscles and ligaments, and it is in this position that painful foot strains exist. The inward movement of the center 50 of weight pivots upon a line drawn from the ball of the great toe to the point where

the heel is in contact with the ground or other supporting surface. Viewed posteriorly, the arc formed by this movement shows that the lateral movement is greatly in excess of any downward movement in the 55 early part of the inward shifting of the weight-bearing center. However, as the inward movement progresses, the downward movement becomes much more appreciable. Flat foot is the result of distorted function 60 due to prolonged faulty position of the foot incident to the shifting of the center of weight, while the position of the bones in the intermediate stages is known as pronation.

65 From the foregoing, it will be evident that prevention of flat foot may be far more effectually obtained by prohibiting the inward lateral movement of the bones than by endeavoring to overcome the difficulty 70 by exerting pressure from below to prevent the downward movement of the arch which, especially in the earlier stages of pronation, is relatively slight. Further, since the downward movement of the bones is directly 75 the result of the inward movement of the weight-center, the desirability of arresting this inward movement is obvious.

Heretofore, it has been the practice to 80 treat pronation of the foot by the use of so-called arch-supports which, as is well known, act as wedges fitting under the arch with the base toward the inner side of the foot. This wedge serves to tilt the foot outwardly which results in maintaining the 85 center of weight in its normal or an exaggerated position in relation to the inner bony margin of the foot. This narrows the space between the inner and the outer margins of the foot, holding the bones in an 90 abnormal position. The disadvantages of arch-supports are well recognized by the medical profession, owing to the fact that, acting as splints, they interfere with the normal movement of the foot and cause 95 suspension of the active function of the muscles and ligaments. Prolonged use of arch-supports, as is well established, leads to actual weakness and atrophy of these tissues. Further, the compression of the 100

blood vessels in the arch of the foot between the body weight and the arch supports of existing types, causes or produces occlusion of the blood vessels, thereby seriously impairing the nourishment of the tissues of the foot.

The object of this invention is to overcome the faults in the present method of treatment of pronation by arresting or preventing the inward movement of the weight-bearing center during the period in which pronation occurs. That is, while the body weight is borne by the posterior and anterior portions of the foot or, in other words, 10 when the center of weight pivots upon a line drawn from the ball of the great toe to the point where the heel is in contact with the ground. This is accomplished by utilizing the body weight to resist the inward movement of the astragalo-scaphoid joint from the initiation of the pronation period to the 20 conclusion thereof.

In one method of carrying out the aforesaid object of my invention, I provide a 25 device which may be simply and economically constructed, which, in functioning, ignores the downward movement of the arch and acts as a "bumper" to inhibit undue inward motion, thereby attacking pronation 30 at its source. Such a device preferably embodies a metallic or other plate possessing a certain degree of rigidity which is shaped so as to be positioned preferably beneath the heel and extend upwardly against the 35 inner side of the foot in the region of the astragalo-scaphoid joint. By forming the device in this manner, the base is positively held in position by the weight imposed upon the heel, thereby maintaining 40 the extension in functioning position relatively to the inner side of the foot. As the body weight progresses and the previously described rotation of the bones of the foot takes place, the inner side of the foot immediately 45 comes in firm contact with the extension of the device which resists continuance of this movement. Simultaneously, the discomfort resulting from contact with the extension stimulates the muscles to pull 50 the foot back into its normal position. At no time does the device come into contact with the arched surface of the sole of the foot, but its entire action is exerted against the inner side of the foot, preferably in 55 or about the area of the astragalo-scaphoid joint.

In order to convey a clear and comprehensive understanding of my invention, I have elected to illustrate and describe certain 60 embodiments of devices which are designed to function to produce the results which I desire to obtain. It will be understood, however, that I do not limit myself to these specific structures, reserving to myself the 65 full range of equivalents, both in structures

and use, to which I may be entitled under my invention in its broadest aspect.

I shall now proceed to describe my invention with reference to the accompanying drawings, and then point out with more 70 particularity the essential elements of novelty therein in the annexed claims.

In the drawings:

Figure 1 is a side elevation of the bones of the foot, showing a form of my invention in operative position with respect thereto;

Fig. 2 is a perspective view of the device shown in Fig. 1;

Fig. 3 is a side elevation of a foot showing a modified form of my invention in operative position with respect to the bones thereof;

Fig. 4 is a sectional view showing the position of my device relative to the shoe, 85 and foot;

Fig. 5 is a perspective of the structure shown in Figs. 3 and 4;

Fig. 6 is a section on the line 6-6 of Fig. 5;

Fig. 7 is a perspective showing a modified means for detachably fastening the device to the heel or other part of the shoe;

Fig. 8 is a section on the line 7-7 of Fig. 7; and

Fig. 9 is a view in perspective of a further modification of my invention.

Referring now to the drawings in detail, in which like characters of reference are employed to designate like parts throughout the several views, the device, which is preferably formed of sheet metal or other suitable material having the requisite rigidity for its intended purpose, comprises a flat base portion 7 adapted to be nailed or otherwise securely fastened to the heel or other solid portion of the shoe 8. One method of fastening is by means of screws 9 passing through the apertures 10 in the base portion 7 of the device. This method may be used where it is desired to make the device a permanent fixture in the shoe, while in those instances where the device is required to be removable for changing from one shoe to another, I have found it expedient to strike up prongs 11 on the under surface of the base 7, which, under the weight of the body, will become embedded in the insole or other portion of the shoe, firmly holding the device against dislodgment.

Extending upward from the base portion 7 of the device is a continuation 12 which is conformed to lie in the region of the astragalo-scaphoid joint, the termination providing a bearing portion 13 to restrain the excessive inward movement of this portion of the foot for the purpose hereinbefore explained.

The device may be encased in an envelop

or shield of leather or other suitable material, as shown at 14, which may be padded, if desired, to afford greater comfort, the said envelope preferably having an extension 14^a adapted to lie beneath the heel, as shown in Fig. 3. Suitable openings are provided in the envelope or shield to permit the screws 9 or other permanent fastening means, or the temporary fastening prongs 11, to pass therethrough, and properly function. In some instances, it may be desirable to incorporate the device in the shoe, in which event it is preferably disposed within the inner lining of the shoe, the base portion 7 under the insole and the extension 12 between a split counter.

In the modification shown in Fig. 9, it will be observed that the base-portion 7 is provided with an elongation 7^a to extend beneath the heel and give the device a slightly increased surface by which it may be positively held in functioning position.

From the foregoing description it will be readily understood that the device described may be considered as a lever fulcrumed at 12^a. Thus the body weight applied against the base portion 7 thereof develops a leverage force upon the upwardly directed portion 12, which force, by reason of the configuration of the device, is translated into resistant pressure against the foot. This pressure is constant from the initial imposition of the body weight upon the posterior and anterior portions of the foot until the heel is raised from contact with the ground. It follows, therefore, that the position of the foot will be controlled by means of a constant resistance during the period in which pronation takes place at the joint formed by the astragalus and scaphoid bones *a* and *b*, respectively. The device having no contact with the arch in the manner of the usual arch supports, the slight pressure exerted by the bearing portion 13 of the device against the astragalo-scaphoid joint causes a patient involuntarily to bring his foot muscles into play to release this pressure, thus strengthening those muscles and ligaments which must cooperate to maintain the foot in proper balance for transmitting the weight from the bones of the leg to the ground in its normal line.

It will be noted that, unlike former devices directed to the alleviation of flat-foot conditions, my invention permits all of the joints of the foot to function with their proper degrees of flexibility and the normal functioning of the muscles and tissues is in no way interfered with or supplanted, the tendency to pronation being treated at its point of inception to cause the foot itself to effect the cure.

I claim:

1. A device for correcting pronation of the foot, consisting of a flat plate formed to

be positioned beneath the sole of the foot, having an integral upwardly directed extension arranged to bear against the inner side of the foot approximately opposite the astragalo-scaphoid joint, said device functioning to resist the inward movement of said joint during the period in which the heel is bearing weight. 70

2. A means for correcting pronation of the foot, consisting of a substantially rigid device embodying a flat portion adapted to lie beneath the foot, and an upwardly directed portion arranged to contact locally with the inner side of the foot approximately opposite the astragalo-scaphoid joint, and means for detachably connecting said device to the inside of a shoe, said upwardly directed portion being adapted to resist inward movement of said joint when the body weight is imposed upon the heel. 75 80 85

3. The combination with a shoe, of means for correcting pronation of the foot, said means consisting of a substantially rigid device having a flat portion adapted to lie beneath the heel and detachably connected to the inside of the shoe, and an upwardly directed portion contacting locally with the inner side of the foot approximately opposite the astragalo-scaphoid joint to resist inward movement of said joint when the body weight is imposed upon the heel. 90 95

4. A means for correcting pronation of the foot, consisting of a substantially rigid device embodying a flat base portion, and an upwardly directed extension, said base portion being adapted to lie beneath the foot and extend from the bearing point of the heel to a point about the middle of the arch, and means for detachably connecting said base to the inside of a shoe, said upwardly directed extension being formed to contact with the inner side of the foot approximately opposite the astragalo-scaphoid joint to resist inward movement of said joint when the body weight is imposed upon the heel, 100 105 110 the soft tissues of the arch of the foot being free of pressure from said device.

5. A device for correcting pronation of the foot, consisting of a support adapted to be positioned beneath the sole of the foot 115 and out of contact with the arch, and having an extension located in the region of the astragalo-scaphoid joint and adapted to contact with the side of the foot opposite said joint to resist inward movement thereof 120 during the period in which the body weight is imposed upon the heel.

6. In a means for correcting pronation of the foot, the combination with a shoe, of an upwardly extending element having a portion in fixed contact with the shoe at a point below the inner border of the foot, said element contacting locally with the inner side of the foot approximately opposite the astragalo-scaphoid joint to resist any tend- 125 130

ency to pronation when the body weight is imposed upon the heel.

7. A device adapted to be inserted in the shoe for correcting pronation of the foot, comprising a flat portion formed to lie beneath the sole of the foot, and a portion extending upwardly from said flat portion in

the region of the astragalo-scaphoid joint and adapted to contact with the inner side of the foot approximately opposite said joint to resist the initial movement thereof when the body weight is imposed upon the heel.

DUDLEY J. MORTON.
